CAN OPENER

Arthur Carp, Hillsdale, Mich.

Application July 13, 1946, Serial No. 683,384

6 Claims. (Cl. 30—15.5)

1

The present invention relates to improvements in can openers of the type disclosed in my co-pending application Serial No. 597,177, filed June 2, 1945, now abandoned.

One object of the invention is to provide an improved can mountable opener which is secured in position on the can at the time the rolling cutter is pierced through the can top and only rotational force on the driver is required to complete the operation.

Another object is to provide an opener of the type described in which the driver and cutter are resiliently mounted relative to each other to yield to the can seam.

A further object is to provide an opener of the type described in which the driver has both arcuate and radial movement toward the cutter upon clamping the opener upon the can.

A still further object is to provide an opener of the type described in which a swinging filler member is provided between the can and the cutter to increase the range of can sizes and shapes capable of being readily opened.

A still further object of the invention is to provide an improved can-mounted opener which requires only an initial clamping pressure at the time the can is pierced and is thereafter propelled around the top of the can to open the same by rotating the driver by one hand, the other hand free to manipulate the can.

These and other objects and advantages residing in the combination, construction and arrangement of parts will be more fully understood from a consideration of the following specification and the appended claims.

In the drawings.

Fig. I is a side elevational view showing one form of the invention in an open position.

Fig. II is a view similar to Fig. I showing the opener in a closed position.

Fig. III is an end elevational view of the invention shown in Fig. I clamped upon a can.

Fig. IV is a fragmentary sectional view taken on line IV—IV of Fig. III.

Fig. V is a perspective view taken from the outer side of a modification of the invention, and shown in opened position.

Fig. VI is a view similar to Fig. V taken from the inner side.

Fig. VII is a side elevational view of the opener shown in Fig. V, but in the closed position.

Fig. VIII is a sectional view taken on line VIII—VIII of Fig. VII, and

Fig. IX is a fragmentary sectional view taken on line IX—IX of Fig. VIII, showing the relationship between the cutter, filler and can.

2

Referring to the form of the invention illustrated in Figs. I to IV, inclusive, the opener comprises a sheet metal member 10 upon which the rotatable cutter 12 is supported upon an angular boss 14. The cutter 12 is mounted upon a stud shaft 16 having a suitable shoulder for abutting against the boss 14 and threaded at its inner end to receive the nut 18 all in a well-known manner. The serrated driver 20 is mounted on an arbor 22 having a bearing in the member 23 carrying a winged handle 24 through which the driver 20 is rotated. The member 23 is preferably of sheet metal and has an adjustable hinge connection with the member 10 through a threaded shoulder stud 26 which extends through a circular opening 28 in the member 10 with a relatively close fit and projects through an elongated slot 30 in the member 23. A filler plate 32 is positioned between the member 23 and the nut 34 threaded upon the outer end of the stud 26.

The members 10 and 23 are formed to provide handle portions 36 and 38 with flanges 40 and 42 being turned back to provide a surface against which pressure is exerted by the fingers and to stiffen the members 10 and 23. A stop portion 44 is provided upon the member 10 to engage with the flange 40 in the manner indicated in Fig. II to determine the fully closed position of the opener.

The lower end of the member 10 has a turned-out flange 46 on which an adjustable shoulder member 48 is mounted. The member 48 has a threaded stud portion 50 to fit through an opening 52 and receives adjustment nuts 54 located upon opposite sides of the flange 46. Turned out from the lower end of the member 23 is an arcuate flange 56 which is wiped across the upper surface of the shoulder 48 when the member 23 is swung from the position shown in Fig. I to the position shown in Fig. II. Through this arrangement, the member 23 is given a radial translational movement relatively to the member 10 as well as a swinging movement, the radial movement being made possible through the provision of the elongated slot 30. Thus the driver 20 upon swinging movement of the member 23 is not only carried toward a plane passing through the axis of the studs 26 and 36 but it also has a radial movement toward the cutter 12. This arrangement increases the space between the driver 20 and the cutter 12 with the opener in its wide open position shown in Fig. I for the reception of the can 57 with a minimum swinging movement of the member 23.

In order to permit the driver 20 to yield rela-

tive to the cutter 12 at the time the seam on the can is encountered the member 23 is provided with a transverse slot 58 terminating in an embossed opening 60. The member 23 is preferably of metal having a reasonable amount of resiliency, so the construction will enable the cantilevered portion 62 of the member 23 upon which the driver 20 is mounted to yield slightly under the pressure of the can seam, to facilitate the travel of the opener over the seam as the opener is driven around the edge of the can by turning the handle 24.

The member 10 is provided with a slot or opening 64 through which the arbor 22 extends upon which the handle 24 is carried. With the handle 23 in the open position shown in Fig. I, the arbor 22 is at one end of the slot 64 and with the handle 23 in the closed position of the opener, the arbor 22 is at the opposite end of the slot 64. With the member 23 in the position shown in Fig. I, the can to be opened has its upper edge inserted between the cutter 12 and the driver 20. The member 23 is then swung into the position shown in Fig. II, which will result in the cutter 12 piercing the can and the upper edge of the can being clamped between the serrated driver 29 and the serrated V groove 66 of the cutter 12. With the edge of the can tightly clamped in this manner, rotation of the handle 24 will result in the opener traveling along the edge of the can with the cutter 12 being rotated by the relative movement between the can top and the cutter 12, the can cover being severed by the cutter 12 as the opener rolls along the top of the can, all in the manner indicated in Fig. III.

To improve the adaptation of the opener to a wide range of can sizes and shapes, the filler plate 32 fixed to the plate 23 by the nut 34 has a nose portion 68 which projects slightly behind the driver 20 but is maintained in spaced relation thereto, moving as a unitary part with the member 23. With the opener fully closed in the manner shown in Fig. II, the nose 68 is disposed in behind the cutter 12 and engages the can to hold it against the cutter 12 and position the latter adjacent the side wall of the can 57. A fixed filler member 69 performs a similar function on the opposite side.

The modification shown in Figs. V to IX, inclusive, is very similar to the construction just described with reference to Figs. I to IV except for the filler member construction and the type of pivotal movement of the hinged parts.

Sheet metal member 70 has an opening 72 to accommodate the hub 74 of the stub shaft 76 upon which the serrated driver 78 is mounted. Supported on the hub 74 is a wing handle 80 through which the driver 78 is rotated.

Supported for pivotal movement in the opening 82 defined in the member 70 is a flanged stub shaft or button member 84 carrying a threaded stud 86 preferably eccentrically located to the axis of rotation of the button 84, for reasons which will be hereinafter pointed out. The sheet metal member 88 has an opening 90 to receive the threaded stud 86. A nut 92 firmly clamps the plate 88 against the face 94 of the button 84 which projects through and slightly beyond the inner face of the member 70 with the result that the members 70 and 88 are capable of relative pivotal movement around the center of the opening 82. By making the opening 82 relatively large and the button 84 correspondingly so, the pivotal joint just described does not loosen up or show appreciable wear over a long period of use.

The upper portion 96 of the member 70 is angularly disposed to the lower portion 98 with a handle portion being provided at 100. Likewise the upper portion 102 of the member 88 is also angularly disposed to the lower portion 104, with the upper portion 102 also functioning as a handle portion. Having the same general contour as the member 70 is a pivotal filler member 106 with an upper handle portion 108 and a lower portion 110 having a pivotal connection at 112 with the lower portion 98 of the member 70. Intermediate its end, filler member 106 has a projection 114 which performs a function similar to the members 68 and 69 of Fig. IV.

Referring to Fig. VI, the lower portion 104 of the member 88 is provided with a shoulder 116 to receive a triangular portion 118 of a member 106. When the members 70 and 88 are swung into their open position as shown in Fig. VI, the shoulder 116 engages with the projection 118 to lock the filler member 106 in the position shown in Fig. VI.

The rolling cutter 120 is mounted upon a stub arbor 122 provided with a shoulder and a threaded stud for mounting the same from the angular portions 96 and the member 70 in the manner illustrated in Fig. VIII.

Referring to Fig. IX, the function of the filler member 106 is illustrated. With the opener in its full open position illustrated in Fig. VI, the upper edge of the can 124 is inserted between the driver 78 and the cutter 120. By applying pressure against the handle portion 102 and 108, the opener moves into a closed position illustrated in Fig. VII. In this position, the operating parts are as shown in Fig. IX. It will be noted that the portion 114 on the filler member 106 is so located relative to the outer wall of the can 124 that the cutting edge 126 of the cutter 120 is closer to the guide wall of the can on one side than it is on the opposite side. This results in the can top being severed at a point directly adjacent the side wall of the can and provides clean cutting and removal of the can top. Preferably the filler member 106 is so shaped and mounted relative to the member 70 that it is spaced from the member 70 in the manner indicated in Fig. IX. When the can to be opened is of larger diameter than that illustrated in Fig. IX, there is enough resiliency in the member 106 to permit the same to be deflected toward the member 70 at the same time it is exerting a pressure upon the side wall of the can which will hold the can relative to the cutter 120 in the manner illustrated in Fig. IX. Through this arrangement, the can opener illustrated in Figs. V to IX is adapted for efficient operation upon a wide range of can sizes and shapes. With square or rectangular cans the member 106 may be urged from the position shown in Fig. IX to a position in actual abutment with the member 70. With a square or rectangular can, as the rounded corner is approached during the opening operation, the resiliency of the filler member 106 will urge the same outwardly relative to the member 70 to momentarily assume the position it would take during the opening of a relatively small diameter cylindrical can. The turned-out tab 128 rides upon the upper edge of the can being opened and assists in supporting the can opener upon the top of the can as it is driven around the can top by rotation of the handle 80.

In operating the can opener illustrated in Figs. V to IX, inclusive, it will be understood that the cutter 120 is hooked over the top of the can to be

opened and the tab 128 will rest upon the upper edge of the can. The operator then squeezes upon the handle 102 and 108 held between the thumb and the fingers. This pressure swings the members 70 and 78 into the closed position shown in Fig. VII to bring the driver 78 and the cutter 120 into the position illustrated in Fig. VIII. With the parts in this position, the rolling cutter edge 126 has penetrated or pierced the cam top and the driver 78 is bearing against the top edge of the can in the manner illustrated in Fig. III. The closing of the can opener has also brought the filler member 106 into the position indicated in Fig. IX, with the cutting edge 126 crowded toward the side wall of the can in the manner illustrated in Fig. IX. With the can opener thus clamped upon the can top in its closed position illustrated in Fig. VII, it is no longer necessary to apply any pressure to the handle 102 and 108 and the can can be opened by merely rotating the handle 80, which will cause the can opener to completely travel around the top of the can. When the seam of the can is encountered, exerting unusual pressure between the driver 78 and the cutter 120, the slot 130 provided in the member 88 will permit the driver 78 to yield slightly to the seam, thus avoiding any momentary excessive application of torque to the handle 80 in order to overcome the obstruction presented by the seam.

Having thus described my invention, what I claim as new and desire to cover by Letters Patent is:

1. A can mountable opener comprising a member, a cutter on said member, a second member, a driver on said second member, a pivotal pin and slot connection between said members at their lower ends to permit limited relative translation movement, handle portions at the upper end of said members, said cutter and driver being mounted on their respective members intermediate said upper and lower ends, said members being pivotal around said connection between open and closed positions to vary the spacing between said driver and said cutter, cam and cam follow means on said members below said pivotal connection for imparting relative translation movement thereto upon relative pivotal movement, portions on said driver and cutter between which the top peripheral edge of the can is clamped with said members in closed position, another portion of said cutter overlapping said first portion of said cutter to pierce and cut the can top inwardly of the peripheral edge.

2. A can mountable opener as defined in claim 1 in which that portion of said second member upon which said driver is supported is yieldable in the plane of movement of said driver toward said cutter by said portion being substantially severed from the remainder of said second member.

3. A can mountable opener as defined in claim 1 in which that portion of said second member on which said driver is mounted is in the form of a yieldable cantilever having an effective ful-

crum at the connection of said portion with the remainder of said second member.

4. A can mountable opener as defined in claim 1 having a filler member upon the driver carrier member supported for movement with this member to engage the can upon movement of said members to a closed position and force the can against the cutter.

5. A can mountable opener comprising a pair of members pivotally connected at their lower ends and having handle portions at their upper ends, a rotatable cutter mounted on one of said members intermediate its ends, a rotatable driver mounted on the other of said members intermediate its ends and closer to said pivotal connection than said cutter, said driver being movable with its associated member into substantially a line between said cutter and said pivotal connection, with rotation of said driver in one direction urging said members together to pierce the can with said cutter and urging said driver toward said line, rotation of said driver in the opposite direction tending to separate said members, said member upon which said driver is mounted being partially severed along a line intersecting said first line between said driver and said pivotal connections to resiliently support said driver relative to said cutter.

6. A can mountable opener comprising a rotary cutter, a rotary driver, separate members on which said cutter and driver are mounted, a pivotal connection between said members, said cutter and driver being in off-set relation to enable the cutter to be positioned on the inside of the top bead of the can and the driver on the outside thereof, said members being pivotal to pierce the can top with said cutter and to clamp the top bead between said cutter and said driver, the pivotal axis of said members and the axis of rotation of said cutter and driver being disposed on substantially the same plane with said cutter and driver clamped upon the top bead of the can to be opened, said member upon which said driver is mounted being partially severed along a line intersecting said first line between said driver and said pivotal connections to resiliently support said driver relative to said cutter.
